UNITED STATES PATENT OFFICE.

JOSEPH E. ZOMNIR, OF SPRINGFIELD, MASSACHUSETTS, ASSIGNOR TO THE DIAMOND MATCH COMPANY, OF CHICAGO, ILLINOIS, A CORPORATION OF ILLINOIS.

MACHINE FOR ASSEMBLING BOOK MATCHES.

Application filed February 7, 1923. Serial No. 617,500.

To all whom it may concern:

Be it known that I, JOSEPH E. ZOMNIR, a citizen of the United States, and resident of Springfield, in the county of Hampden and State of Massachusetts, have invented certain new and useful Improvements in Machines for Assembling Book Matches, of which the following is a specification.

This invention relates to mechanism for assembling book or card matches and the like in a row in order to facilitate the operation of packing them uniformly and compactly in suitable containers; and the invention has for its object to provide mechanism of simple and efficient construction and operation whereby the articles are rapidly arranged side by side with the larger and thinner ends of adjacent articles in opposite relation to each other.

The invention is especially, though not exclusively, designed for use in connection with or as an attachment to the book-match making machine described in Letters Patent of the United States No. 1,073,394, dated September 16, 1913, to which reference may be had.

The invention comprises various features of construction and organization, and principles of operation, which will be hereinafter described and claimed.

In the drawings—

Figure 1 is a side elevation of book assembling mechanism embodying a preferred form of my invention, so much of the book-match machine being shown as is necessary to illustrate the invention.

Fig. 2 is a plan of the mechanism shown in Fig. 1.

Fig. 3 is a transverse horizontal section through the said mechanism in the plane of the axis of the conveyer wheel at the delivery end of the book-match machine; as on the line 3—3 of Fig. 1.

Fig. 4 is a longitudinal vertical section through the mechanism in the plane of the axis of said conveyer wheel, as on the line 4—4 of Fig. 1.

Fig. 5 is a transverse horizontal section in a plane through the cam devices and their actuating mechanism, as on the line 5—5 of Fig. 1.

Fig. 6 is a sectional detail of the cam-actuated reciprocating head for effecting

the oscillation of the turret structure, as on the line 6—6 of Fig. 5.

Fig. 7 is a perspective view of said head and cam, and the associated gearing, including a cam for controlling the operation of certain book-discharging, book-shifting and book-depressing plungers.

Fig. 8 is a transverse horizontal section in a plane immediately above the turret head, showing the plungers retracted; the book conveyer and the turret being at rest, and the latter being at the limit of its left hand or contraclockwise movement and supporting a book in position for transference to the central opening of the turret.

Fig. 9 is a vertical section through the upper part of the turret structure and the receiving end of the trough, the latter being represented as supplied with reversely arranged match books, and the book-depressing and book-shifting plungers, and adjuncts, being shown.

Fig. 10 is a perspective view of the turret, showing the book-depressing plunger above the upper end thereof, and also the basal actuating connections.

Referring to the drawings, 11 designates the delivery end of the table of a book-match machine of the general character illustrated in Patent No. 1,073,394 aforesaid. The endless conveyer 12 upon which the book-matches are formed in the said machine is flexed about suitable wheels at or adjacent the respective ends of the table and is intermittently driven by appropriate mechanism; the wheel at the delivery end of the table being shown at 13. The conveyer comprises an endless steel band having transverse blocks 14 regularly spaced apart on its outer surface to provide a succession of pockets for flat-lying match-books (15) which, in the intermittent travel of the conveyer, are advanced consecutively to the path of discharge, as fully described in said patent.

The mechanism embodying my invention is associated with the delivery end of the book-match machine, and is designed to receive the successive books discharged from the upper run of the conveyer and assemble them side by side, in a row, with the larger and thinner ends of the books alternately reversed, for convenience of packing.

This mechanism, in its preferred form, comprises a centrally throated turret structure 16 having a vertical axis of oscillation and being constructed and arranged 5 to receive the successive books discharged from the conveyer and position them in opposite endwise relation to each other in such a manner that the reversely-located books can be superposed one upon another 10 within the throat of the turret, and thence be advanced into and along a suitable supporting chute or trough 17 located within and extending outwardly beyond the turret. 15 The turret structure comprises a circular head 18 having a central throat 19 therein of suitable form and size to permit a match book to pass flatwise therethrough. The head is mounted to oscillate within a circular opening 20 near the end of the table 11, which end is supported by standards 21 rising from the bed 22 of the book-match machine and also from a supplemental bed 23 conveniently bolted to the main bed. The head 18 is preferably formed on or secured to a vertical casing 24 having a lateral opening 25 therein and also having a depending hub 26, the latter being secured to the upper end of a central shaft 27 that is rotatably mounted in a suitably-disposed bearing 28 included in a substantial supporting frame 29. Fast on the lower end of the shaft 27 is a crank 30 which is connected by means of a link 31 with a head 32 mounted for horizontal reciprocation in a guide casing 33 forming part of the frame structure 29. The head 32 comprises a hollow block having therein two transversely-disposed rolls 34 in spaced relation to each other, the sides 35 of the block being longitudinally slotted, as at 35. Extending transversely of the block and through the slotted sides thereof is a shaft 36 having fast thereon, within the block, an appropriate cam 37 which, by actuation of the shaft, alternately impels the rolls in a manner to effect the positive reciprocation of the block 32, thereby transmitting through the link and crank connection to the vertical shaft 27 oscillatory motion in synchronism with the intermittent motion of the conveyer. The co-operative relation of the parts just described is such that the turret is intermittently swung 40 through an arc of ninety degrees. 45 The shaft 36 has its bearings in the frame structure 29, and is provided at one end with a sprocket wheel 38 that is connected by means of a chain 39 with a wheel 40 on an adjacent parallel shaft 41 having its bearing 50 in the walls of a cam housing 42 supported on the bed 23. On the shaft 41 is a sprocket wheel 43 which is connected with a similar wheel fast on a shaft of the book-match machine. Thus continuous motion is transmitted to the shafts 41, 36. 55

On the upper face of the turret head 18 are two guide-ways which are arranged at a right angle to each other and lead from the periphery of the head to two adjacent sides of the central throat. Each of these guide-ways comprises a pair of ribs 44 secured to the head 18 and spaced apart for the free passage of a book therebetween. Such guide-ways are so disposed that when the turret is oscillated through an arc of ninety degrees, as hereinbefore described, they are positioned alternately in the path of discharge of the books from the adjacent run of the conveyer; one guide-way being located at either the right or the left hand side of the axis of oscillation of the turret while the other guide-way is in the said discharge path. Hence when the turret is thus positioned a book pushed from the conveyer will enter into the proximate guide-way. If then the turret be swung through an arc of ninety degrees to the right or left, as the case may be, the book thus entered in the guide-way will be correspondingly carried and the empty guide-way will be located in book-receiving position. At this juncture the book supported on the turret can be pushed flatwise to a position above the central throat of the turret head, and at the same time another book can be pushed from the conveyer into the adjacent empty guideway. Coincidentally the book positioned above the throat of the turret head can be pushed down into the throat. The books successively discharged from the conveyer are thus received by the turret and positioned thereby in opposite endwise relation to each other and then placed flatwise one upon the other above and depressed through with the thin end of one book at the thick 60 end of the contiguous book, and so on. It is to be noted that the top of the turret head is provided with suitably-disposed lugs 44' which serve as stops for the leading ends of the respective books when they have been correctly positioned above the throat of said head. 65

The superposed books when they are depressed into the throat of the turret as just mentioned enter and progress along the trough 17 which, in the present instance, comprises a curved chute portion which is supported within the turret with its mouth adjacent to and in register with the central throat. The trough, which is fixedly secured to a bracket 45 bolted to the table, extends outwardly through the lateral opening 25 of the turret and is so positioned as not to obstruct the movement of the latter. Preferably the receiving end of the trough is provided with means operative to permit the entry of the succeeding books into the trough but to prevent their upward displacement. Such means, in the present instance, comprise a pair of beveled latch 70

heads 46 which normally overlie the opposite upstanding walls of the trough and are yieldingly supported by depending springs 47 suitably secured to the walls. (See Fig. 9). The books, assembled side by side, progress down the curved portion of the chute as above mentioned and thence through the outward extension, which latter is preferably upwardly inclined in order 10 to facilitate the manual removal therefrom of the assembled books.

The preferred devices for ejecting the successive books from the conveyer and delivering them upon the turret, and for shifting 15 the reversely-disposed books on the turret to the central throat of the latter, comprise three plungers 48, 49, 50, respectively, slidably mounted in suitably-located guides 51 on the table. The plunger 48 is reciprocable in a path transversely of the upper run of the conveyer during each dwell of the latter, so as to impinge against the opposing end of each succeeding book on the conveyer and push it therefrom and into the 20 proximate guide-way of the turret; and the plungers 49, 50 are positioned in longitudinal alinement with each other, and at right angles to the path of the plunger 48, so as to impinge against the books that are alternately located at the respective sides of the 25 turret, and thus push them toward and above the central opening of the turret head.

In the present instance each of the plungers is provided on its upper face with 30 rack teeth 52 with which meshes a gear sector on a suitably-disposed shaft having its bearings in brackets (53') on the table. The shaft 53 of the gear sector 54 that meshes with the teeth of the plunger 48 extends 35 longitudinally of the table and is provided with two spaced apart bevel gears 55 in mesh with similar gears 56 on the shafts 57, 58 which carry the gear sectors 59, 60 that mesh with the teeth of the respective plungers 49, 50, said latter shafts extending 40 transversely of the table. The shaft 53 is provided at one end with a crank 61 that is connected by means of a pitman 62 with a vertical slide 63 fitted to guide-ways in the 45 cam housing 42 previously referred to. The slide has a lateral roll 64 that travels in the race of a cam 65 fast on the driven shaft 41, which cam is contained within the housing. The contour of the cam roll is such that 50 during each dwell of the conveyer and the turret the slide is reciprocated in a manner to impart an oscillatory motion to the shaft 53, through the pitman and crank connection, and thereby oscillate the gear sectors 55, through each dwell of the conveyer and to 55 and simultaneously reciprocate the three plungers.

The preferred means for depressing the succeeding books into the central throat of the turret head comprises a plunger 66 vertically reciprocative directly above the throat.

This plunger is slidably fitted to a guide casing 67 formed in a bracket 68 on the table, said bracket also including a suitable cap member 69 that overlies the turret head and serves to prevent upward displacement 70 of the books thereon. The upper end of the plunger 66 is connected by means of a link 70 with a crank disk 71 on one end of a shaft 72 which has its bearings in the bracket 68 and also in an adjacent bracket 73 75 on the table. On the other end of this shaft 72 is a bevel gear 74 in mesh with a similar gear 75 on a vertical shaft 76 depending through the table and having its bearings in the bracket 73 and also in a bracket 77 on the bed 23. On the lower end of the shaft 76 is a bevel gear 78 in mesh with a similar gear 79 on a short horizontal shaft 80 having its bearings in the bracket 77. This shaft 80 bears a sprocket wheel 81 80 that is connected by means of a chain 82 with a similar wheel 83 on the driven shaft 36. Hence during the rotation of the latter shaft the motion is transmitted therefrom to the shaft 72 and its crank disk in a manner to effect the timely reciprocation of the plunger 66 for the purpose described.

From the foregoing it will be seen that during each succeeding movement of the upper run of the conveyer 12 of the book-match machine, the turret is swung through an arc of ninety degrees, first in one direction and then in a reverse direction, and that during the dwell of the conveyer and turret one of the guide-ways on the latter is located in alinement with a book-holding pocket of the conveyer, the other guide-way is at a right angle thereto on either side of the axis of oscillation of the turret, and the three plungers 48, 49, 50 are positively reciprocated. Hence the plunger 48 pushes a book from the conveyer into the adjacent guide-way on the turret head; one of the plungers 49 or 50 pushes from the other guide-way and above the throat of the turret head a book that was previously inserted in the latter guide-way, and the remaining plunger moves idly above the turret head. When the book is positioned above the throat the vertical plunger 66 is reciprocated in a manner to push the underlying book flatwise through the throat and into the depending chute. A book is entered into the empty guide-way of the turret head, which is positioned adjacent the conveyer at the end of each stroke of the head, and hence the plungers 49, 50 act in alternation upon the books presented thereto at the opposite sides of the head and push them, in 110 opposite endwise relation to each other, to and above the turret throat, through which they are depressed into the chute as just stated, whence the assembled books progress outwardly along the chute and into position 115 for ready removal in series by an attendant.

It is to be understood that my invention is not limited to the specific construction herein disclosed, as the mechanisms may be modified within the principle of the invention and the scope of the appended claims.

I claim—

1. The combination with means for intermittently impelling a row of flat-lying articles with their head portions located at one side of the path of travel, of means for ejecting each succeeding article from the row, a rotary element having guides in angular relation to each other and having a central throat to which said guides lead, means for oscillating said element to position its guides alternately for the reception of the ejected articles, oppositely-acting means at the respective sides of the axis of oscillation of said element for shifting into the central throat the articles positioned in the respective guides, and means for depressing the articles through said throat and in flatwise position.
2. The combination with means for intermittently impelling a row of flat-lying articles with their head portions located at one side of the path of travel, of means for ejecting each succeeding article from the row, a rotary element having guides in angular relation to each other and having a central throat to which said guides lead, means for oscillating said element to position its guides alternately for the reception of the ejected articles, oppositely-acting means at the respective sides of the axis of oscillation of said element for shifting into the central throat the articles positioned in the respective guides, means for depressing the articles through said throat and in flatwise position, and a stationary chute having its mouth in communication with said throat.
3. The combination with a conveyer having a succession of pockets to receive and hold flat-lying articles with their head portions adjacent one longitudinal edge of the conveyer, of ejecting means reciprocable transversely of the conveyer, an element mounted to oscillate on a vertical axis adjacent the conveyer, said element having guides in angular relation to each other and having also a central throat to which said guides lead, means for oscillating the said element to position its guides alternately for the reception of the articles ejected from the conveyer, oppositely-acting means at the respective sides of the axis of oscillation of said element for shifting into the central throat the articles positioned in the respective guides, means for depressing the articles through said throat and in flatwise position, and a stationary chute having its mouth in communication with said throat.
4. The combination with a conveyer having a succession of pockets to receive and hold flat-lying articles with their head portions adjacent one longitudinal edge of the

conveyer, of ejecting means reciprocable transversely of the conveyer, an element mounted to oscillate on a vertical axis adjacent the conveyer, said element having guides in angular relation to each other and having also a central throat to which said guides lead, means for oscillating the said element to position its guides alternately for the reception of the articles ejected from the conveyer, oppositely-acting means at the respective sides of the axis of oscillation of said element for shifting into the central throat the articles positioned in the respective guides, means for depressing the articles through said throat and in flatwise position, and a stationary chute having its mouth in communication with said throat.

5. The combination with a conveyer having a succession of pockets to receive and hold flat-lying articles with their head portions adjacent one longitudinal edge of the conveyer, of ejecting means reciprocable transversely of the conveyer, a turret mounted to oscillate on a vertical axis adjacent the conveyer, said turret comprising a hollow laterally open body having a circular head provided with a central throat and with guides leading thereto in angular relation to each other, means for oscillating said turret to position its guides alternately for the reception of articles ejected from the conveyer, oppositely-acting means at the respective sides of the axis of oscillation of said turret for shifting into the central throat the articles positioned in the respective guides, means for depressing the articles through said throat and in flatwise position, and a stationary chute having its mouth in communication with said throat, said chute extending through the lateral opening of the turret body.

6. The combination with means for intermittently impelling a row of flat-lying articles with their head portions located at one side of the path of travel, of an element located adjacent the path of said row and having guides in angular relation to each other and also having a central throat to which said guides lead, means for oscillating said element to position its guides adjacent the path of the articles, a plunger movable transversely of said path, two plungers movable at right angles to the first named plunger and in alinement with each other above the rotary element, and means for simultaneously reciprocating said plungers, whereby each succeeding article of the row is pushed therefrom into the guide adjacent thereto, and is thereafter pushed by one or the other of the said two plungers to a position above the central throat, means for depressing the articles through said throat, and a stationary chute having its mouth in communication with said throat.

7. The combination with means for inter-

mittently impelling a row of flat-lying articles with their head portions located at one side of the path of travel, of a turret located adjacent the path of said row and having guides in angular relation to each other and also a central throat to which said guides lead, a vertical shaft supporting said turret, a reciprocative head, means for reciprocating said head, and operative connections between said head and the shaft, whereby said turret is oscillated to position its guides alternately adjacent the row, means for moving each succeeding article transversely from the row and into the guide adjacent thereto, means for shifting the article through said guide and above the central throat when the guide is at either side of the axis of oscillation of the turret and at a right angle to its previous position, means for depressing the article through said throat, and a stationary chute having its mouth in communication with said throat.

8. The combination with means for intermittently impelling a row of flat-lying articles with their head portions located at one side of the path of travel, of a turret located adjacent the path of said row and having guides in angular relation to each other and also a central throat to which said guides lead, a vertical shaft supporting said turret, a reciprocative head, means for reciprocating said head, and operative connections between said head and the shaft, whereby said turret is oscillated to position its guides alternately adjacent the row, means, including a plunger and associated gearing, for moving each succeeding article transversely from the row and into the guide adjacent thereto, means, including two oppo-

sitely-disposed plungers and associated gearing, for shifting the article through said guide and above the central throat when the guide is at either side of the axis of oscillation of the turret and at a right angle to its previous position, means, including a plunger and connections, for depressing the articles through said throat, and a stationary chute having its mouth in communication with said throat.

9. The combination with a conveyer having a succession of pockets to receive and hold flat-lying articles with their head portions adjacent one longitudinal edge of the conveyer, of ejecting means reciprocable transversely of the conveyer, an element mounted to oscillate on a vertical axis adjacent to the conveyer, said element having guides in angular relation to each other and having also a central throat to which said guides lead, means for oscillating the said element to position its guides alternately for the reception of the articles ejected from the conveyer, oppositely-acting means at the respective sides of the axis of oscillation of said element for shifting into the central throat the articles positioned in the respective guides, a cap member supported above the said element and having a vertical guide portion directly above the said throat, a plunger vertically reciprocable in said guide portion, and means for reciprocating the said plunger to depress the articles in flatwise position through said throat.

Signed at Springfield, in the county of Hampden and State of Massachusetts, this 3rd day of February, A. D. 1923.

JOSEPH E. ZOMNIR.
